Design No. 18,063, dated February 14, 1888.

1969

1969

UNITED STATES PATENT OFFICE.

CATHERINE SHEILS, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 18,063, dated February 14, 1888.

Application filed January 11, 1888. Serial No. 260,433. Term of patent 3½ years.

To all whom it may concern:

Be it known that I, CATHERINE SHEILS, of the city, county, and State of New York, have invented and produced a new and original Design for a Pattern of a Girl's Costume; and I do hereby declare that the engraved prints accompanying this specification convey to any one accustomed to using paper patterns a clear understanding of how a garment made up by

10 the pattern will appear.

The design shows an overdress and a round walking-skirt. The skirt displays a back drapery that exhibits draping plaits at the center and two loose loops in either side edge. The 15 overdress displays under fronts revealed in V shape below the throat; full vest portions that exhibit their front edges reversed in lapels above the closing and a fullness in their upper

and lower edges; jacket fronts turned back in fancy lapels all the way down the front edges, 20 a full drapery depending from the lower edge of these portions and exhibiting draping plaits in each side edge and a pointed outline at the right side; a close-fitting back that falls in two short tabs between two long narrow tabs; coat-sleeves, and a standing collar.

What I claim as my invention, and desire to secure by Letters Patent, is—

The design for a girl's costume, as shown in the engraved prints accompanying this specification.

CATHERINE SHEILS.
